(57) **CLAIM**

The ornamental design for a low-voltage light, as shown and described.

DESCRIPTION

FIG. 1 is an isometric top view of a low-voltage light.

FIG. 2 is an isometric bottom view thereof.

FIG. 3 is a left side view thereof.

FIG. 4 is a front view thereof.

FIG. 5 is a right side view thereof.

FIG. 6 is a rear view thereof.

FIG. 7 is a top view thereof; and,

FIG. 8 is a bottom view thereof.

The broken lines are presented for the purpose of illustrating portions of the low-voltage light and form no part of the claimed design.
